QUICK DISCONNECT SOCKET HOLDER

Matthew J. Partyka, Mineola, N.Y.

Application September 2, 1955, Serial No. 532,377

4 Claims. (Cl. 340—381)

(Granted under Title 35, U.S. Code (1952), sec. 266)

The invention described herein may be manufactured and used by or for the Government of the United States of America for governmental purposes without the payment of any royalties thereon or therefor.

This invention relates to improvements in lamp holders, and more particularly pertains to improvements in quick disconnect lamp socket holders.

Miniature lamps are mounted frequently in relatively inaccessible positions. As a result, they are difficult to handle when they are to be replaced. Frequently, because of the required positioning of a lamp in a device, the instrument must be dismantled partially to gain access to the spent lamp to be replaced. Considerable time and labor is lost, unless some rapid means to replace the spent lamp bulb is possible. The quick disconnecting means of the subject invention overcomes these difficulties and provides a holder for small lamp bulbs that eliminates the necessity for threading a lamp bulb socket into its holder and also automatically centers the lamp bulb in the correct position to provide the required illumination. In addition, the lamp bulb and socket can be removed readily and replaced even in positions that permit the insertion of only two fingers.

The primary object of the invention is to provide a lamp holder that permits the lamp thereof to be removed facilely for replacement.

Another object is to provide a lamp holder adapted to receive a lamp bulb and without requiring prolonged effort to effect accurate location thereof within the retaining housing.

A further object is to provide means to enable a lamp bulb to be removed and replaced quickly even though the lamp holder is located in a relatively inaccessible position.

Still another object is to provide a lamp holder that will allow replacement of a bulb quickly and accurately, employing only the sense of touch.

Other objects and many of the attendant advantages of this invention will be readily appreciated as the same becomes better understood by reference to the following detailed description when considered in connection with the accompanying drawings wherein:

Fig. 1 is a side elevation of a disconnect socket holder, showing a preferred embodiment of the invention;

Fig. 2 is a longitudinal section taken on line 2—2 of Fig. 1; and

Fig. 3 is a transverse section taken on line 3—3 of Fig. 2.

Similar numerals refer to similar parts throughout the several views.

The socket holder of the invention is adapted to be mounted in operational equipment. It is particularly advantageous when the lamp to be replaced is ordinarily difficult to reach, and would require dismantling of some portions of the apparatus in order to be removed and replaced.

The housing for the lamp socket holder consists of an elongated tubular barrel or housing 10, retained in axial alignment with lamp housing 12 by means of connecting

2

channel body member 14. Terminal pin 16 extends through tubular housing 10 and secures one end of compression spring 18 extending within the housing. The other end of spring 18 is retained at 20 on plunger 22.

5 Channel member 14 is integral with the lower portion of lamp housing 12 and terminates in guide ring 24. Ring 24 aligns with the end of tubular housing 10 and is integral with end 26. Clamp ring 28 extends around ring 24 and the adjacent edge of tubular member 10, securing these two members together by means of set screws 30.

Rod 22 is preferably of solid stock and extends partially within tubular housing 10. Spring 18 normally urges plunger rod 22 forwardly and into housing 12. Collar 32 is secured on the free end of plunger 22 and functions as the means by which the plunger is grasped and is moved back against the force of spring 18. Collar 32 also extends into semi-circular channel 14 (see Fig. 3) and guides plunger rod 22 in its axial movement.

15 Lamp bulb 34 is threaded into lamp socket 36. Lamp socket 36 is freely seated in channel 14 and abuts the forward edge of plunger rod 22. Lamp bulb 34 is threaded into socket 36 and is urged against insulated plug member 38. Plug member 38 is drum-shaped and 20 contains axially aligned apertures 40 and 42. Plug member 38 is preferably of insulation material.

25 Plug member 38 is used when it is necessary to provide a point source of light. Where diffusion of the illumination from lamp bulb 34 is acceptable, plug 38 is not inserted. This allows the light from the lamp bulb to emerge from the larger outlet end of housing 12 as a wide-angled beam.

30 Lead wires 44 are connected to socket holder 36 and lead back to a source of electrical current. Since housing 12 and channel 14 are made of non-conducting material, there is no problem of shorting out the circuit. Obviously, equivalent means of insulation can be substituted.

35 Spring 18 urges plunger rod 22 towards housing 12. Lamp socket 36 is seated freely against the edge of rod 22 and collar 32 and extends at least partly within housing 12. Lamp bulb 34 is threaded into socket 36 and is pushed against plug 38. This stops forward movement of plunger rod 22 and socket 36 and the device is in

40 operational position at all times to provide a narrow light beam. When bulb 34 burns out and is to be replaced, collar 32 is grasped and rod 22 is pulled back against the force of spring 18. Channel 14 confines collar 22 so that axial movement is assured. Socket 36 and its lamp are then removed from the device by gently pulling on the lead wires 44, plunger rod 22 being again allowed to move forward until collar 32 engages housing 12. When lamp 34 has been replaced, plunger rod 22 is again retracted, socket 36 is slipped into place and the plunger rod is again released to urge the socket and lamp into housing 12.

45 In the event plug 38 is not provided, collar 32 can be made adjustable on rod 22 so that lamp 34 is urged directly against housing opening 46.

50 The specific construction of the device can be modified without varying the inventive concept. For example, ring 24 could be threaded and fit within tubular housing 10. In this instance, clamp ring 28 would not be required. Alternatively, ring 24 could be frictionally held on housing 10 by means of a clamping ring. Channel 14 could also be eliminated and be made as a flat connecting strip. Also, a compressible rubber plug could be substituted for spring 18, to provide the same function.

55 70 Obviously many modifications and variations of the present invention are possible in the light of the above

teachings. It is therefore to be understood that within the scope of the appended claims the invention may be practiced otherwise than as specifically described.

What I claim is:

1. A quick disconnect socket holder, comprising a tubular housing, a lamp housing in axial alignment with said tubular housing, a channel body member connecting said tubular housing and said lamp bulb housing, socket means removably retained within said lamp bulb housing and adapted to retain a lamp bulb therein, and an elongated rod extending through said tubular housing into said channel body member and abutting the socket means to help retain the latter in the lamp housing, said lamp housing including a plug member, and an axially extending aperture in said plug member and aligned with the socket means to provide a point source of light.

2. A quick disconnect socket holder, comprising a tubular housing, a lamp housing in axial alignment with said tubular housing, said lamp housing having a light beam opening, an arcuate channel body member connecting said tubular housing and said lamp housing in spaced apart relationship, a socket member removably retained in said lamp housing, a plunger rod having a collar mounted thereon, said plunger rod being slidably retained in said tubular housing and spring means in said tubular housing engaging the plunger rod and adapted to move it slidably through said tubular housing and chan-

nel member to engage the socket member to thereby retain the latter in the lamp housing, said collar abutting the lamp housing to stop continued movement of the plunger rod and providing the means whereby the plunger rod is moved against the force of the spring when the socket holder is to be removed from the lamp housing.

3. The combination of claim 2, and a plug member in said lamp housing, said plug member including aligned apertures to provide a point source of light.

10 4. The combination of claim 1, wherein said lamp bulb housing includes a substantially large outlet opening to allow light from a lamp bulb to emerge as a wide-angled beam when used alone, and said plug member is removably seated in said lamp bulb housing, the axial aperture of said plug member being of lesser diameter than said outlet opening to reduce the amount of light emerging from the socket holder.
